(No Model.)

E. NORTON.
POURING NOZZLE FOR SHEET METAL CANS.

No. 437,232.

Patented Sept. 30, 1890.

UNITED STATES PATENT OFFICE.

EDWIN NORTON, OF MAYWOOD, ASSIGNOR TO HIMSELF, AND OLIVER W. NORTON, OF CHICAGO, ILLINOIS.

POURING-NOZZLE FOR SHEET-METAL CANS.

SPECIFICATION forming part of Letters Patent No. 437,232, dated September 30, 1890.

Application filed April 12, 1890. Serial No. 347,596. (No model.)

To all whom it may concern:

Be it known that I, EDWIN NORTON, a citizen of the United States, residing in Maywood, in the county of Cook and State of Illinois, have invented a new and useful Improvement 5 in Pouring-Nozzles for Sheet-Metal Cans, of which the following is a specification.

My invention relates to pouring-nozzles for petroleum and other cans.

10 The object of my invention is to provide a simple, strong, and efficient construction of valve for closing the opening in the pouring-nozzle, which may be easily and cheaply manufactured, and which will operate to form a certain and tight closure.

15 A further object is to provide a combined filling and pouring nozzle.

20 My invention consists in the novel devices and novel combinations of parts and devices herein shown and described, and more particularly pointed out in the claims.

25 In the accompanying drawings, which form a part of this specification, Figure 1 is a side elevation of a device embodying my invention, showing a portion of the can to which it is applied. Fig. 2 is an enlarged central vertical section. Fig. 3 is a modification showing the application of my improved valve to a simple pouring or non-filling nozzle, such 30 as is shown and described in my pending application, Serial No. 343,240, filed March 10, 1890.

35 In the drawings, A represents the can or a portion thereof; A', its upper head, to which the nozzle is applied in the ordinary V-shaped cap-groove a, surrounding the opening A² through the head.

40 B is the lower disk of the nozzle, which covers the opening A² in the can-head and is soldered in place in the cap-groove a. This cap or nozzle disk B is furnished with a central opening B', through which the can may be refilled and out of which its contents may flow. Surrounding this opening B' is a valve-45 seat b, consisting, preferably, of an inverted groove stamped in the rim or edge of the metal surrounding the opening B'.

45 C is a disk furnished with a screw-threaded sleeve at its inner or upper edge. This screw-threaded sleeve-disk C fits flat upon the cap

or nozzle disk B, and the two disks are secured together by folding the flange or edge of one over the other. The flange or fold b', which secures the disks B C together, I prefer to form on the lower disk B, as shown in the drawings. The act of soldering the cap-disk B in place in the can-head will also serve to simultaneously and securely solder the disks B C firmly together. To facilitate the soldering, I fold over the rim of the disks B C a solder annulus or ring E, so that the solder necessary for uniting the nozzle to the can is applied to the nozzle at the time of its manufacture.

55 D is a disk having a screw-threaded sleeve d, which fits or threads with the screw-threaded sleeve c of the disk C to form the removable screw-cap of the nozzle.

60 F and F' are the upper or dome disks of the nozzle, the same being secured together and to the screw-threaded-sleeve disk D by a flange d' on one of the two outer disks, which is folded over the other two. This securing flange or fold d' is preferably formed or turned on the disk D. The removable screw-cap of 65 the nozzle is thus composed of the three disks D, F, and F'.

70 The disks F F', one or both, preferably both, are furnished with countersinks or pockets f to receive the screw-threaded valve-nut G' of 75 the screw-threaded valve-stem G. The disks F F' are likewise furnished with countersinks or pockets f' to receive the flange h of the pouring-nozzle H. The flange or fold d', which clamps or unites the disks F F' together, thus also serves to rigidly secure in place the valve-nut G' and the pouring-spout H.

80 The valve consists of two disks K and K', having holes k, through which the valve-stem 85 is inserted, and in the lower of which disks the valve-stem is securely soldered.

85 K² is the packing or bearing surface of the valve, consisting preferably of cork or other suitable material. Where the valve-opening 90 is large, as is ordinarily the case in a refilling and pouring nozzle such as is shown in Figs. 1 and 2, the cork disk or packing K² is preferably made annular or in the form of a ring to save material, and in such case the lower disk 95

K' is furnished with an annular offset or seat k^2 to receive the annular packing. The cork or packing disk is firmly and rigidly secured in place by a flange or fold k^2 turned over the same on the dome-shaped strengthening-disk K'. This flange or fold k^2 , folding over the edge of the cork and embracing the intermediate valve-disk K, serves to rigidly clamp or secure the disks K K' together, as well as to fix the packing-disk K² in place. The dome-shaped disk K' serves to strengthen and brace the valve on the valve-stem, so that the valve will be held rigidly in a plane at right angles to the valve-stem and be strengthened so as to prevent the strains to which it is necessarily subjected in closing the valve-opening from breaking or loosening the solder-joint. By this construction, also, it will be observed that the solder-joint between the valve stem and the lower disk is always exposed to view, so that the workman can by inspection readily see whether this solder-joint is tight, and at the same time there is no possibility of leakage around or through the valve, as the cork disk K² fits snugly against the intermediate valve-plate K and forms a tight joint therewith.

In the modification shown in Fig. 3 my improved valve, with the strengthening dome-disk K', is shown as applied to the form of valve described in my previous pending application before referred to. In Fig. 3 the corresponding parts are designated by similar letters of reference, the difference being that the screw-threaded-sleeve disks C and D are both omitted and the dome-disks F and F' thus secured directly instead of indirectly to the cap or valve disk B. In addition to this, of course, the valve in Figs. 1 and 2, being removable, is necessarily an upper or push-down valve, while the valve shown in Fig. 3 is a lower or pull-up valve.

G² is the thumb-piece or handle by which the screw-threaded valve-stem is turned.

45 I claim—

1. The combination of a valve-seat disk B with a valve-stem, a valve secured to said stem and consisting of a cork or packing disk, a sheet-metal disk on which said packing-disk is seated, and a strengthening or dome-shaped disk having its rim or flange folded over the cork disk and clamping the two metal disks and cork disk together, said two metal disks having holes through which the valve-stem is inserted and to the lower or under

one of which said valve-stem is soldered, substantially as specified.

2. The combination, with a valve and a valve-seat disk B, having a valve-opening B' and a valve-seat b, of a screw-threaded-sleeve 60 disk C, a screw-threaded cap-disk D, and dome-disks F F', one of said disks B and C being furnished with a flange folded over the other to secure the same together and one of said disks D and F being furnished with a flange folded over the other for securing said disks and the intermediate disk F' together, said disks F F' having clamped between them a flanged pouring-spout H, substantially as specified.

3. In a combined refilling and pouring nozzle, the combination of a valve-seat disk B, having a valve-opening B' and a valve-seat b, of a screw-threaded-sleeve disk C, a screw-threaded cap-disk D, and dome-disks F F', 75 one of said disks B and C being furnished with a flange folded over the other to secure the same together and one of said disks D and F being furnished with a flange folded over the other for securing said disks and the intermediate disk F' together, said disks F F' being furnished with a valve-nut G', clamped between them, and a valve-stem and valve carried thereby, said disks F F' having also a flanged pouring-spout H clamped between 80 them, substantially as specified.

4. In a combined refilling and pouring nozzle, the combination of a valve-seat disk B, having a valve-opening B' and a valve-seat b, of a screw-threaded-sleeve disk C, a screw-threaded cap-disk D, and dome-disks F F', 90 one of said disks B and C being furnished with a flange folded over the other to secure the same together and one of said disks D and F being furnished with the flange folded over the other for securing said disk and the intermediate disk F' together, said disks F F' being furnished with a valve-nut G', clamped between them, and a valve-stem and valve carried thereby, said valve consisting of a 100 packing-disk K² and metal valve-disks K K', said valve-disk K' having a flange k^2 folded over said packing-disk K² and said valve-stem being soldered to the lower or under one of said sheet-metal valve-disks, and a spout, 105 substantially as specified.

EDWIN NORTON.
